[57] **CLAIM**

The ornamental design for a pouch for a kidney-shaped bottle, as shown and described.

DESCRIPTION

FIG. 1 is a top, left, front perspective view of a pouch for a kidney-shaped bottle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line depiction of a bottle in the pouch is for illustrative purposes only and forms no part of the claimed design.
